Primary Examiner—Melvin B. Feifer*Assistant Examiner*—Dominic Simone*Attorney, Agent, or Firm*—Ostrolenk, Faber, Gerb & Soffen[57] **CLAIM**

The ornamental design for a bugle chime, as shown and described.

DESCRIPTION

FIG. 1 is a top plan view of a bugle chime embodying my new design;

FIG. 2 is a front elevational view thereof; the rear elevational view being a mirror image;

FIG. 3 is a left-hand side elevational view thereof;

FIG. 4 is a right-hand side elevational view thereof;

FIG. 5 is a bottom plan view thereof; and,

FIG. 6 is a cross-sectional view taken along a line VI—VI in FIG. 2, of the bugle chime with sound generating means being omitted.
